ELECTRONIC COUNTER

Werner A. Gieseke, Danville, Ill.

Application February 27, 1946, Serial No. 650,663

10 Claims. (Cl. 235—98)

1

My invention relates to electronic counters and more particularly to a high speed device employing light interruptions on a phototube as a means of setting up impulses in an electronic circuit which are effective to cause the operation of a counting mechanism of any character.

One object of the invention is to provide a counter of the character indicated in which the electronic means are operated by direct current, thus enabling a connected, mechanical registering device to be operated at high speed.

A further object is to provide an electronic counter arranged to convert short electrical impulses set up by objects moving at high speed into impulses of longer duration that allow for the inertia of and are capable of operating the mechanical parts of the counter.

A further object is to devise a counter characterized by the above features in which the impulse broadening stage acts as a trigger for the power stage of the circuit which is coupled to electrical means for operating the registering mechanism of the counter.

These and further objects of the invention will be set forth in the following specification, reference being had to the accompanying drawings, and the novel means by which said objects are effectuated will be definitely pointed out in the claims.

In the drawings:

Fig. 1 is a schematic arrangement showing one method of passing the objects to be counted through the focal point of light rays incident upon a phototube which forms part of an electronic circuit.

Fig. 2 shows a variant method of presenting the objects to be counted to the optical system of the counter.

Fig. 3 illustrates a circuit layout which may be used with either of the arrangements shown in Figs. 1 and 2.

Referring to Fig. 1, the numeral 10 designates a hopper into which the articles to be counted may be deposited manually or mechanically. The hopper includes a delivery passage 11 arranged for gravity feed of the articles and sized to permit only the flow of single articles one behind the other. Each article is dropped through the focal point 12 of an optical system comprising a light source 13 whose rays are focused by a lens 14 for incidence on a phototube 15. Each interruption of the rays on the phototube generates an electrical impulse that is transmitted to an amplifying circuit, generally indicated by the nu-

2

meral 16, which in turn conditions the impulse so that it may be employed to set in operation a counting mechanism 17, all as specifically explained hereinafter in connection with the circuit arrangement shown in Fig. 3.

In Fig. 2, the articles 18 to be counted are deposited in any desired manner on a conveyor 19 which carries the articles successively through the focal point of an optical system comprising a light source 20 and a lens 21. The conveyor belt is characterized by sufficient transparency to enable the light rays to become incident on a phototube 22 which is related to an amplifying circuit 23 and a counting mechanism 24 to accomplish the general operation noted above and as presently described in detail.

The circuit arrangement for effecting the counting action is illustrated in Fig. 3. Generally speaking, the capacity to count at high speed, i. e., as many as one thousand pieces per minute, is due to direct current operation of the circuit stages including the phototube which sends negative impulses to an amplifier that is coupled to a trigger circuit which in turn is connected to a power stage, the latter controlling operation of a mechanical counter through a solenoid, for example, or any type of control mechanism and is particularly suitable for controlling those devices which are characterized by rapid, cycling motions.

Specifically, a power source for the phototube and amplifying phases of the circuit is provided by a transformer 25 having a primary winding 26 and secondary windings 27, 28 and 29. The winding 27 is connected to the directly heated cathode of a duo-diode tube 30 while the plates of this tube are respectively connected to the terminals of the winding 28. Also connected to one terminal of the winding 27 is a wire 31 including in series relation a fuse 32 and a choke coil 33 whose end is connected to ground by a wire 34 which includes a capacitor 35. The winding 28 is center tapped by a wire 36 which connects with the wire 34. This arrangement provides a full wave rectifier employing an L-type filter constituted by the coil 33 and capacitor 35 which supplies direct current voltage for the operation of the stages involving a phototube 36, a pentode amplifier 37 which in conjunction with the associated circuit acts to invert impulses generated by the phototube 36, and a thyratron tube 38 which in conjunction with the associated circuit broadens the impulses received from the amplifier and acts as a trigger

for the power stage of the circuit which is separately supplied by direct current as hereinafter described.

Leading from the junction of the wires 31 and 34 is a wire 39 and connecting the latter to ground is a voltage divider 40 comprising fixed resistors 41, 42 and 43, and a potentiometer 44. A wire 45 connects the potentiometer 44 with the cathode of the amplifier 37 while the plate of the latter is connected by a wire 46 having a fixed resistor 47 with the wire 39. The cathode of the phototube 36 is connected to ground by a wire 48 having a fixed resistor 49 while the anode of the phototube is connected to the voltage divider 40 between the resistors 42 and 43. The control grid of the amplifier 37 is connected to ground by a wire 51 through a resistor 52 and a capacitor 53 is bridged between the wires 48 and 51 on the output ends of the resistors 49 and 52. The resistor 52 and capacitor 53 function as a grid leak bias for the control grid of the amplifier 37.

A wire 54 having a resistor 55 provides connection between the control grid of the trigger tube 38 and the wire 46 at a point between the plate of the amplifier 37 and the resistor 47. The cathode of the trigger tube 38 is connected to a filter comprising a resistor 56 and a capacitor 57 and the plate of the trigger tube is connected by a wire 59 to the wire 39. Also connected to the wire 39 and in parallel with the trigger tube 38 is a wire 61 which includes a resistor 62. The lower end of the wire 61 is connected to a wire 63 which at one end connects with the filter 56-57 and at the opposite end with the power driving stage presently described, and also with a wire 64 including a resistor 65 which leads to ground.

It will be understood that the terminals of the secondary winding 29 are connected to the filament of the amplifier 37 and that this winding is center tapped at 66 for connection to the amplifier cathode. For the filament of the trigger tube 38, a separate transformer 67 is used having primary and secondary windings 68 and 69, respectively. The terminals of the secondary winding 69 are connected to the filament of the trigger tube 38 while a center tapping 70 of this winding connects with the cathode of the trigger tube. For the sake of clearness, the connections referred to in this paragraph have not been illustrated in the drawing.

A separate transformer 71 is employed for the power driving stage of the circuit and it comprises a primary winding 72 and secondary windings 73, 74 and 75. The terminals of the winding 73 are connected to the plates of a duo-diode tube 76 whose cathode is connected to the upper end of a voltage divider 77 comprising the fixed resistors 78 and 79 and potentiometer 80. A wire 81 connects the potentiometer 80 with the cathode of a vacuum type power tube 82 which constitutes the power driving stage of the circuit and whose plate is connected to one end of the coil of a solenoid 83, the opposite end of the coil being joined to a wire 84 that connects with the upper end of the voltage divider 77 and with the cathode of the tube 76. It will be understood that the core of the solenoid is suitably related to the counting mechanism 17 or 24 so that the latter will be actuated when the core is shifted in the manner hereinafter described.

The secondary winding 73 is center tapped by a wire 85 which connects with the input end of the potentiometer 80. Capacitors 86 and 87 are respectively interposed between the wire 85 and the upper end of the solenoid coil, and between the

wires 85 and 81. The potentiometer 80 and capacitor 87 constitute a variable cathode, resistor-capacitor filter for providing a variable cathode biasing of the power tube 82 to establish the correct operating point for the solenoid 83. From the foregoing, it will be obvious that the tube 76 and associated circuit provides a full wave rectifier employing a resistor-capacitor filter for supplying direct current voltage for the operation of the power tube 82 and the solenoid 83.

The power and amplifying stages of the circuit are linked by a resistor 88 which connects the output end of the resistor 56 with the control grid of the power tube 82 and by the wire 63 which connects with the wire 85.

The terminals of the secondary winding 74 are connected to the filament of the power tube 82 and the same winding is center tapped by a wire 89 which connects with the power tube cathode. Power for the light source 13 or 20 may be supplied by the secondary winding 75. The connections referred to in this paragraph, including the light source, are not shown in the drawing for the sake of clearness.

The operation of the circuit shown in Fig. 3 will now be described in connection with the article feeding and optical system shown in Fig. 1, it being understood that the circuit functions in an identical manner for the arrangement illustrated in Fig. 2.

So long as light rays from the source 13 are incident on the phototube 36, the amplifier 37 conducts normally by reason of the variable cathode bias provided by the potentiometer 41 and the grid leak bias constituted by the resistor 52 and capacitor 53. However, when an article to be counted passes through the focal point of the optical system shown in Fig. 1, the shadow cast on the phototube 36 interrupts the conduction of electrons therethrough and the potential at the top of resistor 49, normally positive, drops to that of ground. Then through the action of the capacitor 53 and resistor 52, an impulse of negative polarity is sent to the control grid of amplifier 37 so that the conductance of the latter decreases and its plate voltage increases for the duration of the incoming impulse from the phototube.

It will be noted that regardless of the size or shape of the object to be counted, the negative impulse fed to the control grid of the amplifier 37 retains its standard size because of the time constant characteristics of the resistor-capacitor combination 52-53, or, in other words, the phototube always sends the same impulse regardless of the time interruption of the light rays with respect to any given values of the resistor 52 and capacitor 53.

The trigger tube 38 is normally not ionized due to the grid bias developed across the resistors 47 and 55 and by the cathode bias developed across the resistors 56 and 62, i. e., during periods of light incidence on the phototube. However, when conductance through the amplifier 37 decreases as above described, the voltage drop across the resistor 47 also reduces and the grid bias of the trigger tube 38 is driven towards zero and slightly in a positive direction. Hence, during periods of light interruption, the amplifier 37 and the associated circuit acts as an impulse inverter, changing the negative going input impulse to a positive going, output impulse which triggers the tube 38 as will be presently described. The amplifier also has impedance matching characteristics which match the output of the phototube to the input of the trigger tube.

The positive impulse from the plate of the amplifier 37 causes the trigger tube 38 to ionize and the current flow through the cathode resistors 56 and 65 causes the cathode of the tube 38 to go "more positive" for the duration of the incoming impulse and this positive going, cathode voltage is fed to the control grid of the power tube 82 which thereby becomes ionized. When the power tube 82 fires, current flow through its plate circuit is increased sufficiently to energize the solenoid 83 which may be hooked with a suitable counting or control mechanism.

Normally, the power tube 82 is biased by resistors 56 and 88, and by the potentiometer 80, but when the trigger tube 38 ionizes, this bias is driven towards zero. It will be understood that the trigger tube 38 may be or may not conduct when the phototube is illuminated, depending upon the biasing of the tube 38, but, whatever the situation may be in this respect, the latter's conductance increases when an impulse is fed to its control grid as above described. The trigger tube 38 and the associated circuit function as the impulse broadening stage and is responsible for lengthening the time duration of the impulse fed to the power tube 82 sufficiently to effect the operation of the counting or registering device.

The general object of the entire circuit is to supply a constant impulse to the tube 82 representing the power stage and, to this end, the amplifier 37 feeds a short impulse to the trigger tube 38 which in turn supplies an impulse of longer duration to the power tube.

The specific advantage of that portion of the circuit which includes the trigger tube 38 centers in the cathode filter constituted by the resistor 56 and capacitor 51. Although the impulse fed to the trigger tube 38 may be of short duration, after which this tube may deionize, the time constant of the capacitor-resistor network 57-56 actually controls the width of the impulse fed to the power tube 82. When the tube 38 ionizes, its cathode goes positive and when it deionizes, the capacitor 51, which was charged when this tube ionized, discharges through the resistor 56 to keep the cathode of the tube 38 at that "more positive" potential for a time controlled by the characteristics of the 57-56 network.

The trigger tube 38 is deionized by lowering its plate-to-cathode potential to a value equal to the extinction potential of the tube. When the tube 38 fires, the heavy conduction therethrough increases the resistance drops across the resistors 56 and 65, the latter forming part of a voltage divider including the resistor 62 which is connected to the power supply wire 39 and hence to the plate of the tube 38. Since increased conduction through resistor 56 renders the upper end thereof more positive with respect to the opposite end, which ends are respectively connected to the cathode of the trigger tube and through the voltage divider including the resistor 62 to the plate of the same tube, the cathode becomes more positive with respect to the plate, thus reducing the plate-to-cathode potential to a value equal to the deionizing potential.

It is thus possible to control the time duration of the impulse firing the power tube 82 as necessitated by the time delay required for the operation of the associated mechanical device before the solenoid 83 is deenergized. In other words, without this time delay or impulse broadening

and by reason of the short impulse set up by an article moving through the optical system, there would not be sufficient time for the counter, due to its inertia, to perform its allotted task. My improved arrangement therefore is particularly suitable for high speed counting, including those articles which are too light in weight to actuate a conventional switch or trigger.

It will be understood that the values of the resistors and capacitors will be adjusted and related as the particular operating circumstances require.

I claim:

1. In a device for registering the passage of a succession of articles, the combination of an optical system comprising a light source and a phototube for receiving rays from the source, means arranged to pass the articles through the focal point of the system, direct current operated, electronic means associated with the phototube comprising means for inverting impulses set up by the phototube when the light rays thereon are interrupted by a passing article, a trigger tube for receiving the inverted impulses and a power tube fired by the trigger tube, a resistor-capacitor filter associated with the cathode of the trigger tube and the control grid of the power tube whereby the time duration of each impulse fed to the power tube is lengthened, and solenoid means connected to the plate of the power tube and energized by the firing of the power tube, and the solenoid means being adapted for connection to a registering device.
2. In a device for registering the passage of a succession of articles, the combination of an optical system comprising a light source and a phototube for receiving rays from the source, means arranged to pass the articles singly through the focal point of the system, direct current operated, electronic means comprising an amplifier, a resistor-capacitor coupling associated with the cathode of the phototube and the control grid of the amplifier whereby an impulse of constant size is fed to and is inverted by the amplifier when the light rays on the phototube are interrupted by a passing article, a trigger tube for receiving the inverted impulse and a power tube fired by the trigger tube, a resistor-capacitor filter associated with the cathode of the trigger tube and the control grid of the power tube whereby the time duration of each impulse fed to the power tube is lengthened, and solenoid means connected to the plate of and energized by the firing of the power tube, the solenoid means being adapted for connection to a registering device.
3. In a device for registering the passage of a succession of articles, the combination of an optical system comprising a light source and a phototube for receiving rays from the source, means arranged to pass the articles singly through the focal point of the system, a normally deionized, power tube, solenoid means having its coil in series with the plate of the power tube and adapted for connection to a registering device, means for supplying direct current voltage to the power tube and direct current operated, electronic means responsive to impulses set up by the phototube when the light rays thereon are interrupted by a passing article and associated with the power tube, said electronic means comprising means for inverting the impulses and a trigger tube for receiving the inverted impulses.

and feeding them to the power tube for firing the same, and a resistor-capacitor filter associated with the cathode of the trigger tube and the control grid of the power tube whereby the time duration of each impulse fed to the power tube is lengthened sufficiently to enable the solenoid means to actuate the registering device.

4. In a device for registering the passage of a succession of articles, the combination of an optical system comprising a light source and a phototube for receiving rays from the source, means arranged to pass the articles singly through the focal point of the system, a normally deionized, power tube, solenoid means having its coil in series with the plate of the power tube and adapted for connection to a registering device, means for supplying direct current voltage to the power tube, and direct current operated, electronic means responsive to impulses set up by the phototube when the light rays thereon are interrupted by a passing article and associated with the power tube, said electronic means comprising an amplifier, a resistor-capacitor coupling associated with the cathode of the phototube and the control grid of the amplifier whereby an impulse of constant size is fed to and is inverted by the amplifier when the rays are interrupted, a trigger tube for receiving the inverted impulses and feeding them to the power tube for firing the same, and a resistor-capacitor filter associated with the cathode of the trigger tube and the control grid of the power tube whereby the time duration of each impulse fed to the power tube is lengthened sufficiently to enable the solenoid means to actuate the registering device.

5. A device for counting impulses of short duration comprising a phototube intermittently subjected to light rays, direct current operated, electronic means associated with the phototube comprising means for inverting impulses set up by the phototube when the light rays thereon are interrupted, a trigger tube for receiving the inverted impulses and a power tube fired by the trigger tube, a resistor-capacitor filter associated with the cathode of the trigger tube and the control grid of the power tube whereby the time duration of each impulse fed to the power tube is lengthened, and a counter having an actuating coil with inductive characteristics connected to the plate of and energized by the firing of the power tube.

6. A device for counting impulses of short duration comprising a phototube intermittently subjected to light rays, direct current operated, electronic means associated with the phototube comprising an amplifier, a resistor-capacitor coupling associated with the cathode of the phototube and the control grid of the amplifier whereby an impulse of constant size is fed to and is inverted by the amplifier when the light rays on the phototube are interrupted, a trigger tube for receiving the inverted impulses and a power tube fired by the trigger tube, a resistor-capacitor filter associated with the cathode of the trigger tube and the control grid of the power tube whereby the time duration of each impulse fed to the power tube is lengthened, and a counter having an actuating coil with inductive characteristics connected to the plate of and energized by the firing of the power tube.

7. A device for counting impulses of short duration comprising a phototube intermittently subjected to light rays, a normally deionized, power tube, a counter having an actuating coil with in-

ductive characteristics in series with the plate of the power tube, means for supplying direct current voltage to the power tube and direct current operated, electronic means responsive to impulses set up by the phototube when the light rays thereon are interrupted and associated with the power tube, said electronic means comprising means for inverting the impulses and a trigger tube for receiving the inverted impulses and feeding them to the power tube for firing the same, and a resistor-capacitor filter associated with the cathode of the trigger tube and the control grid of the power tube whereby the time duration of each impulse fed to the power tube is lengthened sufficiently to effect operation of the counter.

8. A device for counting impulses of short duration comprising a phototube intermittently subjected to light rays, a normally deionized, power tube, a counter having an actuating coil with inductive characteristics in series with the plate of the power tube, means for supplying direct current voltage to the power tube and direct current operated, electronic means responsive to impulses set up by the phototube when the light rays thereon are interrupted and associated with the power tube, said electronic means comprising an amplifier, a resistor-capacitor coupling associated with the cathode of the phototube and the control grid of the amplifier whereby an impulse of constant size is fed to and is inverted by the amplifier when the rays are interrupted, a trigger tube for receiving the inverted impulses and feeding them to the power tube for firing the same, and a resistor-capacitor filter associated with the cathode of the trigger tube and the control grid of the power tube whereby the time duration of each impulse fed to the power tube is lengthened sufficiently to effect operation of the counter.

40 9. In an apparatus for counting impulses of short duration including a phototube intermittently subjected to light rays, an amplifier, a resistor-capacitor coupling associated with the cathode of the phototube and the control grid of the amplifier whereby an impulse of constant size is fed to and is inverted by the amplifier when the light rays on the phototube are interrupted, a trigger tube responsive to the inverted impulses, a power tube fired by the trigger tube, a resistor-capacitor filter associated with the cathode of the trigger tube and the control grid of the power tube whereby the time duration of each impulse fed to the power tube is lengthened, and a counting device in the output circuit of the power tube.

55 10. In an apparatus for lengthening impulses of short duration to enable their being counted by a counting device including a phototube intermittently subjected to light rays, an amplifier, a resistor-capacitor coupling associated with the cathode of the phototube and the control grid of the amplifier whereby an impulse of constant size is fed to and is inverted by the amplifier when the light rays on the phototube are interrupted, a trigger tube responsive to the inverted impulses, a power tube fired by the trigger tube and arranged for connection to the counting device, and a resistor-capacitor filter associated with the cathode of the trigger tube and the control grid of the power tube whereby the time duration of each impulse fed to the power tube is lengthened.
